UNITED STATES PATENT OFFICE

2,280,573

FILAMENT TRANSPORTING METHOD AND APPARATUS

John Flaws, Jr., Cleveland Heights, Ohio, assignor to General Electric Company, a corporation of New York

Application November 16, 1938, Serial No. 240,779

5 Claims. (Cl. 176—4)

My invention relates to a process and apparatus for handling coiled filaments for incandescent lamps and the like and more particularly to a process and apparatus for feeding filaments to mounting apparatus and transferring said filaments from their place of manufacture and inspection to said mounting apparatus.

The usual process of handling lamp filaments consists in placing small quantities thereof in closed containers following inspection and then transporting said containers to a place where said filaments are assembled with the remaining lamp parts. The filaments are manually removed from the container to small piles either on automatic mounting apparatus or on trays from which they are taken manually and mounted. Both steps of this process are objectionable, the first because it allows the filaments to rub on each other and the coils thereof to interlock, and the second because the filaments are so difficult to separate because of their size and tangled condition.

To avoid these objections, one object of my invention is to provide a process and apparatus for keeping the filaments separated from the time of inspection following their manufacture to the time they are fed into the mounting machine. Another object of my invention is to provide a convenient process and apparatus for feeding the filaments to the mounting machine as required while they are in their separated relation. Another object of my invention is to provide a convenient magazine for transferring and shipping a relatively large quantity of filaments in individual containers to the point of use which allows the release of said filaments at definite and regular intervals. Other objects and advantages of the process and apparatus of my invention will be apparent from the detailed description which follows of the one species thereof shown in the accompanying drawings.

In the drawings, Fig. 1 is a perspective view of a filament inspection table, a filament loading strip or magazine, apparatus for passing the strip before the table so that the filaments can be placed in the pockets thereof, and controlling means for said apparatus which is diagrammatically shown therewith; Fig. 2 is a perspective view of a portion of the loading strip on a larger scale; Fig. 3 is a side elevation of apparatus for releasing the filaments from said loading strip and the wiring diagram for the control apparatus shown therewith; Fig. 4 is an elevation of the opposite side of said apparatus; Figs. 5 and 6 are elevations, partially in section, of a filament feeding drum and a rewinding spool for the loading

strip, respectively, with the drive means for both shown therewith; and Fig. 7 is a side elevation of a portion of operation control means of said feeding apparatus.

The first operations in the process of handling filaments 10 according to my invention consist in the inspection and the manual insertion thereof into the pockets 11 of the loading strip or magazine 12. The inspection consists in the visual examination of the filaments 10 by an operator seated before the table 13 which in this instance is provided with a glass plate 14 for supporting said filaments 10 and other apparatus (not shown) for directing additional illumination onto the top and bottom thereof. The table 13 may, for instance, also be provided with optical means for projecting an enlarged image of the filament 10 onto a screen adjacent thereto. The loading strip 12 can be a formed or molded strip of metal, rubber, paper or other suitable material but in this instance is made of a relatively thin strip of stainless steel having pockets or indentations 11 formed at regular intervals therealong and sufficiently large to hold single filaments 10. The loading strip 12 as shown in Fig. 2 is of any suitable length with one end wound on the spool 15 and the free portion extending through the channel in bar 16 on the forward edge of the table 13 and about the spool 17. Following inspection, the filaments 10 are separated by the operator and either lifted or slid into the pockets 11 of the loading strip 12 which is moving at a uniform rate from right to left at such a speed as to present empty pockets 11 to the loading position as they are required. The movement of the loading strip 12 is brought about by the grooved drum 18 which is shaped to engage the pockets 11 in the strip 12 and which is driven from a source not shown but diagrammatically represented by the electric motor 19. The drum 18 is mounted on the shaft 20 which in turn is held by the brackets 21 and 22 on the upper surface of the table 13 and is driven from shaft 23 through the gears 24 and 25, the vertical shaft 26 and the gears 27 and 28. The motor 19 may, for instance, be connected to shaft 23 by a speed reducer not shown. The loading strip 12 is pulled from the spool 15 by the rotation of the drum 18 and turns the spool 15 against the resistance of a brake (not shown) engaging the shaft 29 on which it is mounted. Knob 30 which is threaded on shaft 29 keeps the spool 15 in position whereas the notched drum 31 which is pivoted on a stud extending from the bar 16 keeps the loading strip 12 in engagement with the

former drum 18. That portion of the loading strip 12 adjacent the drum 18 is directly in the line of movement of the operator's right hand and is protected therefrom by the plate 32 which also forms a rest therefor.

After passing before the operator, the loading strip 12 passes into operative relation to the finger 33 of a control means which stops the movement thereof when the pocket 11 engaged by said finger 33 is found to be empty or contain more than one filament 10. In this way, the operator is notified of the improper arrangement and can correct it so that the loading belt 12 will function correctly in the feeding apparatus and a definite number of filaments 10 will be known to be occupying a previously counted and marked number of pockets. The finger 33 is mounted on the end of an arm 34 pivoted on the pin 35 in the bracket 36 and is carried into engagement with the loading strip 12 and filaments 10 therein by the weight of said arm 34. The bracket 36 is fastened to the bar 16 and bridges the channel in which the loading strip 12 is located. When more than one filament 10 is encountered, the arm 34 is raised above its normal position and the contact 37 carried thereby is brought into engagement with the stationary contact 38 which completes a circuit through the secondary of the transformer 39 and the coil of the relay 40. The supply circuit to the electric motor 19 includes the armature 41 and contact 42 of the relay 40 which pulls said armature 41 from engagement with said contact 42 when the circuit through the coil thereof is completed. As shown, the transformer 39 is connected to the line for its supply of electric current. When an empty pocket 11 is encountered by the finger 33, the arm 34 moves to a lower position than normal and a second contact not shown on said arm 34 and another contact (also not shown) mounted on the bar 16 are brought into engagement. These contacts are connected to transformer 39 and the coil of the relay 40 and causes the circuit to the electric motor 19 to be broken in the same manner as when more than one filament 10 is located in the pocket 11.

Further movement of the loading strip 12 carries it under the sealing strip 43 which is introduced at this point to cover the top of the loading strip 12 and seal the filaments 10 into the pockets 11 thereof. The sealing strip 43 is preferably made from a material not likely to leave threads or other contamination on the filament 10 and in this particular instance is made of a transparent material manufactured under the trade name "Cellophane" by the E. I. Du Pont de Nemours & Co., Wilmington, Delaware. In some instances, the sealing strip 43 can be dispensed with providing the lower surface of the loading strip 12 is such as to seal the pockets 11 therein when said loading strip 12 is coiled tightly. The sealing strip 43 passes to the loading strip 12 from the supply spool 44 which is pivotally mounted on the bracket 45 and is pulled from the spool 44 against the resistance of a brake (not shown) engaging said bracket 45 and the shaft 46 to which said spool 44 is attached. Both the sealing and loading strips 43 and 12 pass under the roller 47 and the weight 48 on the way to the spool 17 and are pressed together so the filaments 10 cannot escape by said weight 48. The roller 47 and weight 48 are pivoted on the pin 49 carried by the end of bar 16 which allows the weight 48 to raise with the sealing strip 43 as the spool 17 is filled. The spool 17 is turned

in a counterclockwise direction by the shaft 50 on which it is mounted and pulls on the loading strip 12 with sufficient force to keep that portion thereof between the feeding drum 18 and said spool 17 tightly stretched at all times. The shaft 50 is supported by the bracket 51 extending from the table 13 and is turned with the necessary force to keep the proper tension in the loading strip 12 by the frictional engagement of the drum 52 on the end thereof with the band 53 carried by the disc 54. One end of the band 53 is fastened to the disc 54 by the stud 55, whereas the other end is connected to said stud 55 through the spring 56 which tends to contract and draw the band 53 tightly about the drum 52. The disc 54 is pivoted on the end of the shaft 50 and is driven through the bevel gear 57 which meshes with the bevel gear 58 on the drive shaft 23.

In the instance shown, the loading strip 12 has a definite length which includes an intermediate portion containing a known number of pockets 11 which are filled with filaments 10 and end portions in which said pockets 11 are partially filled with solder. The solder prevents the placing of filaments 10 in these portions of the strip 12 and fills only the opposite ends of the pockets 11 so as not to interfere with the operation of the finger 33. The end portions of the loading strip 12 are of sufficient length to hold it in place at the inspection table 13 while the pockets 11 of the intermediate portion thereof are filled with filaments 10. The end of the loading strip 12 is wound on the spool 17 manually and keeps said strip 12 from unwinding and spilling the filaments 10 contained within the pockets 11 thereof. Any convenient means such as a paper sticker can be used for holding the ends of the loading strip 12 in place. After the end of the loading strip 12 is fastened down, the spool 17 on which it is mounted is removed from the shaft and either stored or shipped to the place where said filaments 10 are mounted. Since the filaments 10 are contained within sealed chambers, possibility of contamination and injury during storage and shipping is completely eliminated.

To take advantage of the separated relation of the filaments 10 within the loading strip 12, I prefer to feed them automatically with the apparatus of my invention shown in Figs. 3 to 7 inclusive. This feeding apparatus provides a spindle 60 on which the spool 17 containing the loading strip 12 is placed and automatically pulls said loading strip 12 from said spool 17 after the empty end portion thereof is threaded through the apparatus and attached to the rewinding spool 61. As shown, the loading strip 12 and sealing strip 43 pass under the top and bottom portions 63 and 64 respectively of the guide and then separate, the loading strip 12 going about the feeding drum 65 and the sealing strip 43 going to the rewinding spool 66. The lower portion 64 of the guide is attached to the collar 67 pivotally mounted on a sideward extending boss 68 of the feeding drum 65 as shown in Fig. 5 and is pulled down by the weight 69 so that the top portion 63 of the guide presses down on the sealing strip 43 and holds it in place until loading strip 12 is properly engaged by the feeding drum 65. To prevent the filaments 10 from adhering to the sealing strip 43 after it separates from the loading strip 12, said sealing strip 43 is wiped by a finger 70 which is mounted on the block 71 on the collar 67 and which causes said filaments 10 to fall back into the pockets 11 in the feeding strip 12 from which

they came. The sealing strip 43 is wound on the spool 66 as rapidly as it is separated from the loading strip 12 by the automatic rotation of the shaft 72 on which said spool 66 is mounted and engages the studs 73 extending sideward from the disc 74.

The feeding drum 65 is provided with transverse notches in its periphery which accommodate the indentations formed by the pockets 11 in the loading strip 12 and is provided with raised flanges 75 at both sides which engage the regularly shaped edges of said strip 12. The loading strip 12 is advanced by regular and intermittent movements of the feeding drum 65 and as withdrawn from the spool 17 causes both spool 17 and the shaft 60 on which it is mounted to turn. The spool 17 is held on the shaft 60 by the knob 76 and turns against the friction produced by the brake band 77 which engages the drum 78 also mounted on said shaft 60. The brake band 77 is anchored by the stud 79 extending from the yoke 80 which also supports shaft 60 and is pulled tight about the drum 78 by the spring 82 which engages stud 79 and a nut on the rod 83 on the free end of the brake band 77. This type brake is also preferably used to retard the movement of spools 15 and 44 of the loading strip feeding apparatus previously shown and described. Movement of the feeding drum 65 is caused by rotation of shaft 84 on which it is mounted which in turn is driven from the ratchet wheel 85 through the gears 86 and 87. The ratchet wheel 85 is mounted on a sideward extending boss of gear 86 and is engaged by the pawl 88 on the lever 89 which together with gear 86 is mounted on the stud 90. Both shaft 84 and stud 90 are supported by the stationary standard 91 which extends upward from the frame of the mounting machine (not shown) and engage said standard 91 through the brackets 92 and 93 respectively. The pawl 88 is held against the ratchet wheel 85 by the spring 94 which engages said pawl 88 and the pin 95 on which it is mounted and advances the ratchet wheel 85 when the lever 89 is moved to the right (Fig. 4). The lever 89 is one part of an operating system actuated by the filament mounting machine in order to operate in proper time relation to the operations thereof and is connected through the link 96 to the arm 97 which in turn is operated by lever 98 through engagement of rod 99 therewith. The arm 97 and lever 98 as shown in Fig. 7 are both pivoted on the pin 100 extending from the bracket 101 and operate together when the rod 99 is pushed endward by the solenoid 102 so as to extend into the aperture in lever 98. The lever 98 is actuated by mechanism of the mounting machine (not shown). During the return swing of lever 89 which carries said lever 89 to the left (Fig. 4), the ratchet wheel 85 is kept from turning by the second pawl 103 which pivots on a pin extending from the bracket 93 and is kept thereagainst by a resilient finger 104 only partly shown extending from said bracket 93.

The rotation of the feeding drum 65 soon moves the open pockets 11 carrying the filaments 10 from below the finger 70 to a position behind the shoe 105 which closes said pockets 11 and keeps the filaments 10 in position therein. In this instance, the shoe 105 extends to a position directly below the center of said drum 65 and over the feeding table 106 of a filament mounting machine of the type disclosed in my prior Patent 1,907,532 which issued May 9, 1933. The move-

ments of the feeding drum 65 are such that a pocket 11 within the loading strip 12 is advanced beyond the end of the shoe 105 by each indexing movement thereof so that the filament 10 therein is freed and drops to definite position on the table 106. The operation of the mounting machine which advances the filament 10 from this point engages said filaments 10 through the studs 107 which as shown move to the left (Fig. 3) and carry the said filament 10 out of this position before another filament 10 is released from the loading strip 12. The shoe 105 is attached to the bracket 92 and is apertured to give the finger 108 access to the center portion of the loading strip 12. The finger 108 normally rides on the face of the loading strip 12 and the filaments 10 within the pockets 11 thereof as the drum 65 turns but moves to a new position, when a pocket 11 is engaged which does not contain a filament due to improper filling thereof or the emptying of the loading strip 12. This change in position of the finger 108 is, for instance, used to light a warning light indicating that a filament will not be fed when the empty pocket 11 passes from under the shoe 105 or to stop the operation of the feeding device and can also be used to control operation of the mounting machine if desired. The finger 108 in this case is attached to the arm 108' which, in turn, is attached to a pin 109 extending through a portion of bracket 92 and is pulled against the face of the loading strip 12 and filaments 10 by the contraction of the spring 110 which extends between posts in arm 108' and the shoe 105. When an empty pocket 11 is encountered, the pin 109 is turned by the arm 108' so that the contact 111 which is mounted on the arm 112 on the other end of said pin 109 is brought into engagement with the stationary contact 113 which is mounted through insulating arm 110' on the bracket 92. These contacts 111 and 113 are connected to the frame of the machine which is grounded and to the secondary of the transformer 114 respectively and serve to complete the circuit to the warning lamp 115 and the solenoid 102 which are connected to said secondary and are grounded to the frame of the machine. The operation of the solenoid 102 moves the core 116 so that the rod 99 is withdrawn from the aperture in lever 98 and the filament feeding apparatus is rendered inoperative. This movement of the core 116 compresses the spring 117. After the feeding apparatus has been inspected by an operator and the contacts 111 and 113 have been separated, the spring 117 expands and the rod 99 again moves into the aperture in lever 98 making the apparatus operative.

The empty loading strip 12 passes from the feeding drum 65 to the spool 61 which, as shown in Fig. 6, is mounted on the shaft 119 supported by the yoke 120. The spool 61 is turned indirectly by the chain 121 which meshes with the sprocket 122 mounted on the collar of the driven gear 87 and the sprocket 123 pivoted on the shaft 119. The pulley 124 which is mounted on a flange extending from the sprocket 123 operates shaft 119 through the friction drive provided by the drum 125 on shaft 119 and the friction band 126 anchored to said pulley 124 through stud 127 and engaging said drum 125. As shown in Fig. 4, one end of the friction band 126 is fastened directly to the stud 127 whereas the other end is fastened to the rod 128 extending therethrough and is pulled by the expansion of the spring 129. The pulley 124 also functions as drive means for the spool 66 on which the sealing strip 43 is

wound which it engages through the belt 130 and the pulley 131 on the shaft 72. Slippage of the belt 130 on the pulley 131 absorbs the excessive driving movement of said belt 130 which is placed under the desired tension by adjusting the position of the pulley 131. The pulley 131 and the spool 66 on the opposite end of shaft 72 are positioned by movement of the arm 132 about the bolt 133 which fastens said arm 132 to bracket 134. Bracket 134 on the other hand is fastened to a standard 135 extending from a stationary portion of the mounting machine not shown and supports through the yokes 80 and 120 and the shafts 60 and 119 held thereby the respective spools 17 and 61. The bracket 101 fastens the standard 135 to the standard 91 to make a more rigid unit.

The detailed structure of the spools 15, 17 and 61 of the loading strip filling and feeding apparatus is preferably alike since the spools must be interchanged during my process. As shown in Fig. 6, each spool is provided with one portion 136 comprising the hub 137 and the flange 138 and a second portion 139 having the flange 140 and mounted slidably on the hub 137 of the first. During the periods the loading strip 12 and perhaps the sealing strip 43 are being removed or wound onto said spools, the flanges 138 and 140 are separated somewhat so as to give free movement thereof but when the spools are being removed from the apparatus or held in storage the resilient facings 141 of said flanges 139 and 140 are forced against the sides of the loading and sealing strips 12 and 43. This movement of the flanges 138 and 140 is made possible by the movable second portion 139 of the spool which bears against the flange of the knob 142 and takes a position governed by the extent the hollow center portion of said knob 142 is screwed into the hub 137. The movable portion 139 of the spool is engaged by a plurality of pins 143 (only one of which shows in Fig. 6) which are carried by the hub 137 and which are moved into engagement with said movable spool portion 139 by the expansion of the springs 144. The springs 144 are located about a portion of the pins 143 and in a well in the hub 137 and butt against said hub 137 and the head of said pins 143 which extend into similarly shaped apertures in the movable spool portion 139. The pressure of the pins 143 against the movable spool portion 139 causes it to move outward when the knob 142 is unscrewed whereas the presence of the pins 143 in the apertures of said movable spool portion 139 causes both portions 136 and 139 to turn together. Although the resilient facings 141 on the flanges 138 and 140 of the spools, which in this case are made from rubber, seal the edges of both the loading strip 12 and the sealing strip 43 so that all moisture, lint and other foreign substance may not reach the filaments 10, it is not always necessary to provide this apparatus as the edges of the loading strip 12 and the sealing strip 43 when wound on a spool are drawn tightly together and seal the pockets very effectively. In this latter case, the spools may be permanently attached to the apparatus and the loading strip 12 may conveniently be wound on a hollow core (such as shown for the sealing strip in Fig. 1) which can be slid on and off the spools with the loading strip 12 and sealing strip 43 in place thereon. The filaments

10 in this case are also sealed in separate pockets or chambers, which prevents their contamination, and can be shipped and stored with safety although more care is required in handling to prevent injury to the loading strip 12 and the unwinding thereof.

What I claim as new and desire to secure by Letters Patent of the United States is:

1. In combination with a filament conveyor carrying means for supporting filaments in individually spaced relationship, feeding apparatus comprising means for supporting a coiled flexible strip having pockets therein containing individual coiled filaments, means for uncoiling said strip and for guiding it past a delivery position adjacent said conveyor, and means for causing filaments to be transferred individually from said strip to the supporting means on said conveyor.

2. In combination with a filament conveyor carrying means for supporting filaments in individually spaced relationship, feeding apparatus comprising means for supporting a coiled flexible strip having pockets therein containing individual coiled filaments, means for uncoiling said strip and for guiding it past a delivery position over said conveyor with the pockets thereof in an inverted position, and means for retaining the filaments in the pockets of said strip until said delivery position is reached, said feeding apparatus and conveyor being arranged to operate in proper time relation whereby individual filaments drop from said strip at said delivery position so as to be spaced on the supporting means of said conveyor.

3. Apparatus for feeding coiled filaments comprising an unwinding spindle for supporting a coiled flexible strip having pockets therein containing individual filaments, a rewinding spindle for receiving said strip, a drum member around which said strip passes in its path between said spindles to invert said strip, and means for retaining the filaments in the pockets of said strip until a predetermined delivery position is reached where the filaments drop from said pockets.

4. Apparatus for feeding coiled filaments comprising means for supporting a coiled flexible strip having pockets therein containing individual filaments, a rotatable drum around which said strip is passed, means for indexing said drum to cause the strip to be advanced, and a shoe member engaging the portion of the strip on said drum to retain the filaments in the pockets of said portion until the strip passes from under said shoe when the filaments drop from said pockets.

5. Apparatus for feeding coiled filaments comprising means for supporting a coiled flexible strip having pockets therein containing individual filaments, means for uncoiling said strip and moving it to a discharge position, means for releasing the filaments from the pockets in said strip at said delivery position, a movable finger located adjacent the path of travel of said strip at a location ahead of said delivery position, means for moving said finger into engagement with the filaments or into the pockets of said strip in the absence of filaments in said pockets, and means operable upon entry of said finger into an empty pocket for discontinuing the operation of the means for uncoiling and moving said strip.

JOHN FLAWS, JR.
